CLAIM

I claim the ornamental design for a blower servicing tool, as shown and described.

DESCRIPTION

FIG. 1 is a top, front perspective view showing my new design, with the view showing an elongate up-standing portion of the tool that has a hexagonal cross-section, and an elongate transversely extending handle portion of the tool that has a cylindrical cross-section;

FIG. 2 is a bottom, rear perspective view similar to FIG. 1; FIG. 3 is a front elevational view, it being understood that a rear elevational view is identical hereto;

FIG. 4 is a right side elevational view, it being understood that a left side elevational view is identical hereto;

FIG. 5 is a top plan view thereof; and,

FIG. 6 is a bottom plan view.

In the drawings, broken lines comprised of distinctively relatively shorter dash marks indicate planes beyond which the claimed design does not extend.

In the drawings, broken lines comprised of distinctively relatively longer dash marks depict environmental subject matter that forms no part, portion, element or component of the claimed design.

In each of FIGS. 2 and 6, a broken-line circle located in a central region of a bottom surface of the blower servicing tool depicts an unclaimed boundary of an opening.

1 Claim, 2 Drawing Sheets
